UNITED STATES PATENT OFFICE.

DAVID IRWIN GARRETSON, OF NEW YORK, N. Y.

FIRE-EXTINGUISHER.

No. 926,481.

Specification of Letters Patent.

Patented June 29, 1908.

Application filed April 4, 1908. Serial No. 425,158.

To all whom it may concern:

Be it known that I, DAVID IRWIN GARRETSON, a citizen of the United States, residing at New York, in the county of New York and 5 State of New York, have invented new and useful Improvements in Fire-Extinguishers, of which the following is a specification.

My invention relates to fire extinguishers in which the liquid is discharged by the expansive force of gas.

One of the objects of my invention is to provide a fire extinguisher that can be made to release compressed carbonic acid or other gas in installments or continuously to suit the 15 will of the operator for the purpose of creating a pressure which will force the liquid from the extinguisher.

Another object of my invention is to provide means for creating a pressure within the 20 tank at the same instant that the discharge passage is opened; and to provide means for closing the discharge passage at the same instant that the pressure is cut off.

Another object is to make allowance for 25 the contraction and expansion of the liquid in the tank due to variations in the temperature;

Another object is to provide a device 30 which permits of the use of non-freezing compounds in fire extinguishers.

Other and further objects will appear from the following specification.

In the drawings, Figure 1 is a front elevation of a fire extinguisher embodying my invention; Fig. 2 is a view partly in section showing the extinguisher when not in use; Fig. 3 is a view similar to Fig. 2, showing the relative arrangement of the parts when the extinguisher is in use; Fig. 4 is a plan view of 40 the top; Fig. 5 is an inside view of the top; and Fig. 6 is an elevation of the cartridge and means for opening the discharge-valve therein. Fig. 7 is a cross section of the lower end of the gas cartridge showing the 45 pin valve.

Referring to the drawings, in which the reference characters refer to the same parts on all views,—a shell or tank 1 provided at its upper open end with an interrupted lug 50 thread 2, is surmounted by a flanged head-casting 3 adapted to be firmly but releasably secured thereon by means of lugs 4 upon the head-casting 3. Brazed to the head-casting 3 and depending therefrom, is a discharge-pipe 5 provided at its lower end with a screen or strainer 6. Approximately mid-way of the

height of the discharge-pipe 5, is soldered or otherwise securely fastened thereto, a small bracket 7 provided with an upwardly projecting pin 8 to be hereinafter referred to. 60 Surrounding the pin 8 and supported by the bracket 7, is a resilient member, preferably a spring 9, having secured thereto at its upper end a washer 10 to be referred to hereafter.

Referring more especially to Figs. 2, 3 and 5, the head-casting 3 will be seen to be provided with a slotted spherical recess or depression 11 within which an offset cam portion 12 of the valve-key 13 is permitted to revolve to operate the cartridge 20 as explained hereafter. The valve-key 13 is provided with a passage 14 and rotatably mounted 70 within a cylindrical protuberance 15 upon the head-casting. It is provided at its outer 75 end with a goose-neck 16 and a lever 17 having attached thereto, a hose 18. In the outer end of the hose, is secured a nozzle 19 made without a stop-cock to render it impossible to cut off the out-flow during the generation of 80 pressure within the tank. The steel cartridge 20 for containing compressed carbonic acid or other gas is of a well known design and needs no detailed description. Within its lower end is provided a spring retained 85 valve adapted to be forced open to permit the outflow of confined gas when the cartridge is forced downwardly over the pin 8.

The pin valve is shown in detail in Fig. 7. The cap 25 is screwed into the neck of the 90 cartridge by means of the threads 26, until the flange 27 abuts against the end of the cartridge. The upper end 28 of this plug acts as a valve seat with which the inside valve 29 engages, to control the flow in and out of the 95 cartridge. The valve 29 is screw threaded at 30 upon a spindle 31 which passes down into the neck of the plug and is provided with an enlarged head 32. Between the head 32 of the spindle and the shoulder 33 of the plug 100 there is placed a spiral spring 34 which keeps the valve normally closed. When in position within the tank, said cartridge is held against lateral displacement by the discharge pipe 5 and the lugs 21, upon the under side of the cover 3. The lugs 21 are limited in length to permit the cartridge to be inserted and withdrawn by shifting its lower end sideways.

Referring now to the valve-key 13, (shown 110 best in Figs. 2 and 3), the inner end of the passage 14 is provided with a larger hole 22

through which the liquid is permitted to flow when the extinguisher is in use, and a smaller hole 23 which registers with a corresponding vent-hole 24 when the valve-key is in its normally closed position. From the drawings, it will be apparent that the larger hole 22 which communicates with the discharge pipe 5 when the valve-key is in its fluid-discharge position, is disconnected from said discharge pipe during the normally closed position of the valve-key.

The method of operating the extinguisher may now be readily understood and is as follows:—Allowing the hose to hang downward with the valve-key in the position shown in Fig. 2, the spring 9 is compressed by pressing down upon the washer 10 when the cartridge may be easily slipped into position with the valve of the cartridge directly over the operating pin 8. Upon releasing the spring 9, the washer 10 immediately snaps into position against the flange surrounding the cartridge valve. Upon filling the tank with the fire-extinguishing liquid, the apparatus is ready for use. By raising the lever 17 (which constitutes the outer end of the valve-key), upwardly in either direction, the cam-movement of the offset portion 12 forces the cartridge down over the pin 8 which opens the valve in the cartridge and allows the gas to escape therefrom. The pressure thus created in the tank, forces the liquid through discharge pipe 5 from whence it may be directed in any desired direction by means of the nozzle 19. When the valve-key-lever 17 reaches a horizontal position while moving upwardly, the vent-hole is closed while the larger hole 22 is being opened and by the time the cartridge has been forced downwardly sufficiently far to force its valve open, the hole 22 has opened completely. To cut off the flow, the lever 17 is returned to its lowered position whereupon the supply of carbonic acid gas is cut off simultaneously with the cessation of the flow of the liquid.

It will be seen that the vent-hole 23 is adapted to relieve any residual pressure in the tank when the same is no longer in use, while at the same time, a convenient means is provided for allowing for expansion and contraction in the liquid due to changes in temperature to which the tank may be exposed.

Owing to the simple construction of the head-casting and the means provided for releasably securing the same to the tank, a quarter turn is all that is needed to lock or unlock the head-casting. As shown in the drawings, the entire mechanism of the extinguisher is attached to the head-casting which permits the apparatus to be prepared for operation with a minimum expenditure of time and effort. Further advantages will be apparent in the simple construction, ease of manipulation and the creation of pressure

within the tank only at the times when the liquid is being used.

Having thus described my invention, the following is what I claim and desire to secure by Letters Patent:—

1. In a fire extinguisher, the combination with a tank for liquid, of a head therefor, a liquid discharge pipe depending from the head, a normally closed cartridge slidably mounted upon said discharge pipe, means carried by the discharge pipe for opening said cartridge, a valve for controlling the flow of liquid from the discharge pipe and a cam connected with said valve adapted to slide the cartridge along the discharge pipe. 75

2. In a fire extinguisher, the combination with a tank for liquid, of a head; a discharge-pipe for liquid depending therefrom, a valve therefor; a gas-cartridge slidably suspended from the head and provided with a spring-retained gas-valve; a pin for engaging said valve; and means adapted to open the discharge-pipe valve and to slide the cartridge into engagement with the valve-engaging pin. 80

3. In a fire extinguisher, the combination with a liquid containing tank, having a vent, of a normally closed gas retaining cartridge adapted to discharge in said tank, normally closed discharge pipe for said tank and means adapted to simultaneously open the gas cartridge and discharge pipe and close said vent. 90

4. In a fire extinguisher, the combination with a tank for containing a liquid; a discharge pipe therefor provided with a valve; a gas-cartridge slidable on the discharge-pipe and provided with a valve; a pin attached to the discharge-pipe and adapted to engage the valve of the cartridge; and manually operated means for simultaneously operating the valve in the discharge-pipe and moving the cartridge into engagement with the pin. 100

5. In a fire extinguisher, the combination with a liquid containing tank, of means for creating a pressure therein and a pivotal depending distributing pipe exterior of said tank and adapted when swung on its pivot to control the pressure creating means in said tank and the discharge of the liquid from the said tank. 115

6. A fire extinguisher comprising a tank for liquid; a head provided with a recess and adapted to form an air-tight closure for the same; a rigid discharge-pipe depending from the head; a bracket rigid thereon and provided with a vertically projecting pin; a washer mounted resiliently upon said bracket; a valved gas cartridge seating at one end within the recessed head-casting and supported in a vertical position by said washer; and a valve-key for controlling the flow of liquid from the discharge-pipe and provided at one end with an offset-cam for 120 125 130

forcing the gas-cartridge down upon the vertically projecting pin.

7. A fire extinguisher comprising a tank for liquid; a discharge-pipe for said tank; a 5 gas-reservoir within the tank and provided with a normally closed valve; and a valve-key adapted to act as a valve for said discharge-pipe and vent hole, said valve-key being provided at one end with means for 10 controlling the flow of gas from the gas-reservoir and at the other with a hollow passage for the discharge of the liquid.

8. In a fire extinguisher, the combination with a tank for liquid, of a head therefor, a 15 gas reservoir adapted to discharge in the liquid tank, a liquid discharge pipe suspended from the head, a valve-key comprising an angular tube having outlets for the discharge pipe and for a vent for the liquid 20 chamber, said outlets being adapted to be opened and closed alternately and said valve-key having a cam portion adapted to

control the flow of gas from the gas reservoir.

9. In a fire extinguisher, the combination 25 of a liquid tank, a gas cartridge adapted to discharge in the liquid tank, a normally closed discharge pipe in the tank and a rotatable outlet key adapted to simultaneously cause the discharge of the gas from the 30 gas cartridge and to open the discharge pipe and provided with an aperture which is adapted to allow the release of pressure in the liquid tank when the gas cartridge is closed and to be closed when the outlet key 35 is turned to open the gas cartridge.

The foregoing specification signed at New York city, New York, this 20th day of February, 1908.

DAVID IRWIN GARRETSON.
